UNITED STATES PATENT OFFICE.

GEORGE D. MERRILL, OF EAST ORANGE, NEW JERSEY.

DESIGN FOR A SPOON OR SIMILAR ARTICLE.

SPECIFICATION forming part of Design No. 33,413, dated October 23, 1900.

Application filed August 10, 1900. Serial No. 26,529. Term of patent 3½ years.

To all whom it may concern:

Be it known that I, GEORGE D. MERRILL, a citizen of the United States, residing at East Orange, county of Essex, State of New Jersey, 5 have invented and produced a certain new and useful Design for a Spoon or Similar Article; and I do hereby declare the following to be a full, clear, and exact description of the invention, such as will enable others skilled in the art to which it appertains to make and use the same.

This invention relates to a new and useful design for a spoon or similar article.

The object of my invention is to provide a spoon of the character described with certain peculiar distinguishing features of configuration which, combined with the other portions of the spoon, impart a strikingly novel and artistic effect to the article as an entirety. 15
20 The accompanying drawing shows the article of manufacture in elevation, dotted lines indicating a spoon-bowl and fork-tines.

The straight stem *a* has the spoon-bowl at one end and a laterally-projecting head *d* at the opposite outer end. The inner portion *b* 25 of the stem tapers from the spoon-bowl longitudinally of the stem and is reduced toward the outer end thereof. This short tapered portion *b* is encircled by the spiral groove *c*, formed around and longitudinally thereof, 30 from the bowl to the end of the taper.

Having thus fully described my invention, what I claim is—

The design for a spoon, substantially as shown and described. 35

In testimony whereof I affix my signature in presence of two witnesses.

GEORGE D. MERRILL.

Witnesses:

J. M. MERRILL,
ALBERT HOLLOWELL.
